MATERIAL SCREENING AND FEEDING
MECHANISMEdwin A. Glynn and Stanley Marvin, Lodi, Calif.,
assignors to Super Mold Corporation of California, Lodi, Calif.

Application February 8, 1943, Serial No. 475,090

2 Claims. (Cl. 209—284)

This invention relates in general to a material screening and feeding mechanism, and in particular is directed to a mechanism for this purpose especially designed for use in connection with the screening and feeding of dry placer mineral in the course of dry concentrating thereof to recover the values.

One of the objects of this invention is to provide a material screening and feeding mechanism which includes an axially elongated rotary screen having unique means associated therewith to thoroughly mix the material which passes through the screen, and to then feed such material downwardly from the mechanism in evenly distributed relation longitudinally of the screen, as is necessary to accomplish equality of feed of the screened and mixed material to a longitudinal bank of dry concentrating units or tables which the machine includes below the screen.

Another object of the present invention is to provide a material screening and feeding mechanism which comprises an elongated rotary screen supported on a suitable frame in driven and slightly downwardly sloping relation, a helical screw mounted on and surrounding the screen in outwardly projecting relation, and a material receiving trough below the screen in which the lower portion of the helical screw runs, whereby to mix screened material in the trough and to feed said material evenly over a longitudinal spillway formed by one top edge of said trough.

A further object of this invention is to provide a material screening and feeding mechanism, as in the preceding paragraph, in which the trough is relatively shallow but generally V-shaped in cross section, the side of said trough which includes said spillway forming top edge comprising initially separate longitudinal plates, and means adjustably mounting the uppermost one of said plates whereby the spillway forming edge thereof may be selectively inclined downwardly from adjacent the intake of the screen so as to regulate the spill over said spillway to a substantially equal amount throughout its length.

A still further object of the invention is to construct the material receiving trough, which is disposed below the rotary screen, so that one side of said trough, while normally closing along the bottom edge with the corresponding edge of the other side of the trough, is mounted for lateral separating movement whereby to open a longitudinal gap in the bottom of the trough and permit discharge of all material therefrom.

A further object of the invention is to produce a simple and inexpensive device and yet one

which will be exceedingly effective for the purpose for which it is designed.

These objects we accomplish by means of such structure and relative arrangement of parts as will fully appear by a perusal of the following specification and claims.

In the drawings similar characters of reference indicate corresponding parts in the several views:

Figure 1 is a side elevation of the mechanism.

Figure 2 is a plan view of the same with the rotary screen removed.

Figure 3 is an enlarged cross section on line 3—3 of Fig. 1.

Referring now more particularly to the characters of reference on the drawings, the mechanism comprises an elongated rotary screen 1 disposed with its axis at a slight downward slope from the intake end of the screen; said screen being rotatably supported by a bearing 2 and rollers 3 on a suitable frame F which includes transversely spaced end legs 4. Material to be screened is fed into the upper end of the rotary screen by suitable means such as a chute 5.

A helical screw in the form of an outwardly projecting vane 6 is secured exteriorly on the rotary screen 1 and extends from end to end thereof on a relatively long pitch; said vane being of substantial width radially of the rotary screen.

Downwardly converging, transverse frame members 7 support longitudinal plates 8 and 9 which include downwardly extending edge flanges 10 which seat on said frame members 7; said plates 8 normally engaging along their lower or bottom edges and diverging upwardly therefrom to form a shallow but generally V-shaped trough 11, which is inclined to correspond to the slope of the screen. The flanges 10 of the plate 9 are fixed to the corresponding and supporting frame members 7, while the flanges 10 of the plate 8 slidably seat on the corresponding frame member 7 whereby to permit of upward sliding movement of plate 8 in a lateral direction. The purpose of movably mounting the plate 8 is so that the same may be shifted laterally to open a gap in the bottom of the trough and consequent emptying of the latter when necessary.

Such lateral movement of the plate 8 is accomplished through the medium of a plurality of pivotally mounted links 12 connected between the uppermost flange 10 of plate 8 and cranks 13 fixed on a longitudinally extending shaft 14 suitably journaled on the frame to one side of and parallel to the trough. Adjacent one end the shaft 14 is fitted with a radial actuating lever 15.

It will be seen that with outward swinging movement of lever 14 the plate 9 will be drawn upwardly to open a gap between adjacent lower edges of plates 8 and 9, or along the bottom of the trough.

The side of the trough opposite plate 9 is somewhat wider and includes a longitudinally extending plate 16 disposed parallel to and above plate 8; the lower edge portion of plate 16 overlapping and engaging the upper edge portion of said plate 8. At its upper or outer edge the plate 16 is formed with a depending flange 17 which is attached to the adjacent frame members 7 by means of U bolts 18. The upper edge of plate 16, indicated at S, forms a spillway, the downward inclination of which, longitudinally of the machine, may be altered by adjusting the plate 16 by means of the U bolts 18. In other words, the plate 16 can be set so that the downward inclining downward inclination of the axis of the rotary screen, and which may be desirable as will hereinafter appear.

In operation the plate 9 is normally closed with the plate 8, and as the dry placer material is fed into the rotary screen 1 from the chute 5 the portion thereof which passes through the screen falls into the trough, while the residual portion which does not pass through the screen discharges from the lower end thereof and is carried away by a suitable conveyor (not shown).

The rotary screen revolves in the direction shown by the arrow in Fig. 3, and the pitch of the helical screw 6 is such that with rotation of the screen the lower portion of the screw tends to move material in the trough up the side thereof comprised by plates 8 and 16 and to discharge said material over the spillway formed by upper edge S of the latter plate. Also with such movement of the material by the screw, an effective mixing action is obtained, which assures a proper admixture of the fines with the remainder of the screened material before the latter is discharged over the edge S and falls downwardly for treatment at the dry concentrating units or tables (not shown) but which are disposed therebelow.

By adjusting the degree of inclination of the spillway S relative to the inclination of the rotary screen the amount of material flowing over the spillway may be regulated so that at all points in the length thereof the amount of spilling material is equal. There is a tendency for a greater portion of the screened material to enter the trough from the screen adjacent the upper end

portion of the latter, and thus if the spillway paralleled the screen axis, a greater amount would flow over the upper end portion of the spillway than at other points therealong. To overcome this the plate 16 is adjusted so that the spillway 5 has a greater degree of inclination than the screen axis, and this causes material which would otherwise spill adjacent the upper end portion to remain in the trough for discharging over spillways at a lower point.

From the foregoing description it will be readily seen that we have produced such a device as substantially fulfills the objects of the invention as set forth herein.

While this specification sets forth in detail the present and preferred construction of the device, still in practice such deviations from such detail may be resorted to as do not form a departure from the spirit of the invention, as defined by the appended claims.

Having thus described our invention, what we claim as new and useful and desire to secure by Letters Patent is:

1. A material screening and feeding mechanism comprising a rotary screen having a helical screw on the outside thereof, a frame assembly disposed beneath the screen in supporting relation thereto, and a material receiving trough supported by said frame assembly lengthwise of and below said screen, the lower circumferential portion of said screen and screw running in the trough; the frame assembly including a plurality of V-shaped frames disposed in side by side but spaced relation, and said trough comprising a pair of longitudinally extending side plates disposed in diverging relation from normally engaged lower edges, downwardly extending longitudinal flanges on the edges of said plates seating on said frames, another plate disposed lengthwise of one of said side plates, partially lapping the upper edge portion of the latter and extending laterally at an upward incline, a down-turned flange on the upper edge of said other plate seating on said frames, and means adjustably securing said other plate in connection with said frames.

2. A material feeding and screening mechanism as in claim 1 in which said last named means comprises inverted U-shaped bolt units fixed on and projecting from the downturned flange on said other plate in straddling relation to said V-shaped frames.

EDWIN A. GLYNN.
STANLEY MARVIN.
